W. H. Prescott

UNITED STATES PATENT OFFICE

JOHN A. STEIN, OF NEW YORK, N. Y., ASSIGNOR TO AMERICAN MACHINE & FOUNDRY COMPANY, A CORPORATION OF NEW JERSEY

CIGARETTE MACHINE DRIVE

Application filed May 9, 1927. Serial No. 189,923.

This invention relates to an improvement in a cigarette machine drive, particularly a drive for duplex cigarette machines operating at very high speed and making two cigarette rods at the same time.

The two cigarette rods in the present machine are run side by side, each having a separate tobacco feed, and each having its own printer, wrapper tape, rod former, paster, sealer, and catcher, only the cutoff and ripper being common to both rods. The drives and mounts of the various component parts are so arranged that each rod making mechanism can be operated independently of the other when a break occurs in the continuity of either rod. The machine is designed to make 1600 cigarettes per minute, i. e., 800 from each rod. The speed of the machine is therefore 800 R. P. M.

In the old cigarette machines which operated at speeds between four and six hundred per minute, little difficulty was encountered in starting the mechanism smoothly. But in the new high speed machines, operating at 800 R. P. M., the inertia of the mechanisms has seriously interfered with smooth starting, and resulted in greater wastage of tobacco and paper while the machine was picking up speed from 0 to 800 R. P. M., the greater part of the difficulty being encountered as the speed approaches maximum. It is the main object of the present invention to overcome this difficulty by producing a machine which may be started slowly and then accelerated gradually until maximum speed is reached. With this and other objects not specifically mentioned in view, the invention consists in certain constructions and combinations which will be hereinafter fully described and then specifically set forth in the claims hereunto appended.

In the accompanying drawings, in which like characters of reference indicate the same or like parts, Figs. 1 and 1a are side elevations of a drive constructed in accordance

with the invention; Figs. 2 and 2a are sectional plan views of the same; Fig. 3 is an end view from the line 3—3 in Fig. 1a, showing the drive of the feed mechanism for one of the cigarette rods; Fig. 4 is a plan view showing the clutch control of the main drive shafts of the two groups of working parts; Fig. 5 is a detail of the clutch mechanism; Fig. 6 is a side elevation of the entire drive control; Fig. 7 is an end view of the same as seen from the line 7—7 in Fig. 6; Fig. 8 is a section through the control mechanism on the line 8—8 in Fig. 6; Fig. 9 is a section through the control mechanism on the line 9—9 in Fig. 6; and Fig. 10 is a sectional plan view of the catcher drive, taken on the line 10—10 in Fig. 1.

In carrying the invention into effect, there is provided a constant-speed source of motion such as a power or line shaft, a main machine shaft from which the working parts of the machine derive their motion, a speed-varying gearing connecting the source of motion and the main machine shaft, and controlling means whereby said gearing is caused to start said machine shaft at sub-normal speed and then accelerate said speed, until maximum speed is attained, without producing wastage of tobacco and paper. These various means may be varied in construction within the scope of the claims, for the specific drive selected to illustrate the invention is but one of numerous possible concrete embodiments of the same. The invention, therefore, is not to be restricted to the precise details of the structure shown and described.

Referring to Figs. 1, 1a, 2 and 2a: A and B are the two cigarette rods, C indicates the two cigarette wrapper reels, the lower reel serving the rear rod A and the upper reel serving the front rod B. D indicates a double printer having two drums, dies, ink rollers, etc., for placing a name or monogram on each cigarette length of wrapper. E indicates a duplex feed mechanism having sepa-

rate tobacco chambers and discharge chutes for the two cigarette rods. F indicates the two wrapper tapes, G the two rod formers, H the two pasters, J the two rod sealers, K the common cutoff, and L the two cutoff guides. N indicates the two separator belts which receive the cut cigarettes from the cutoff K, separate the same and deliver them to the two catchers O. P is a chute into which defective cigarettes are thrown to be cut open by the ripper Q. And M is the driving motor or constant speed source of motion.

All working parts of the machine are mounted on the main frame 11 which is supported on the pedestals 12. Both sections of the machine are driven by the motor M. The motor pulley 14, through a silent chain 15, drives the pulley 16 of a variable-speed transmission gearing 17 of the well known Reeves type. The gearing includes a pulley 18 which, through a silent chain 19, drives the main clutch pulley 20 mounted on the main drive shaft 21. The latter is supported in the bearing brackets 22, 23, 24 and 25 on the frame 11.

The Reeves drive used, is provided with any conventional means for simultaneously separating the conical pulley sections 2a and 2b (Fig. 2a), while at the same time bringing together the pulley sections 3a and 3b, and vice versa, in response to a movement of the control rod 298 in one direction or the other, in order to change the speed at which the shaft 232 is rotated by belt 17. As illustrated, this is accomplished by means of two bars 4 and 5 pivotally secured to the pulley sections, as shown, in a manner permitting rotation thereof, said bars being pivoted to the frame of the drive at 7 and 8. One end of each of these bars is swung towards and away from each other by a screw shaft 9 having right and left hand screws engaging swiveled blocks on said ends of the bars. This screw shaft is rotated in one direction or the other to change the relative positions of the pulley sections in response to movements of the control rod 298 by a belt 9a running over pulleys on the screw shaft 9 and a pulley loosely mounted on the drive shaft 232, which latter pulley is rotated in either direction by the drive shaft 232 in response to a combined clutch and reversing gear 10, of a well known type, to which the rod 298 is connected for controlling the same, and which revolves said screw shaft 9 a number of turns in either direction, depending on the position to which the control rod 298 is moved and is then disengaged by a lever 11 having a connection to one of the bars, until the rod is again moved. On the shaft 21 is mounted a gear 26 meshing with gears 27 and 28 on shafts 29 and 30 operating the cigarette rods A and B, respectively. The shaft 29 has a worm 31 driving a wormgear 32, while the shaft 30 has a worm 33 driving a wormgear 34. The wormgear

32 is keyed to a shaft 35 driving, through a ratchet, 36, the printer drum 37 of the cigarette rod B. Similarly, the wormgear 34 is mounted on a sleeve 38 of the shaft 35 and, through a ratchet 39, drives the printer drum 70 40 of the cigarette rod A.

The main shaft 21 carries a gear 41 which, through an intermediate gear 42, drives a gear 43 mounted on a jack shaft 44. The latter has a gear 45 which, through an intermediate gear 46, drives a gear 47 on a shaft 48 which carries worms 49 and 50 driving, respectively, spiral gears 51 and 52. These spiral gears are keyed on shafts 53 and 54, carrying the printer dies 55 and 56. The gear 57 on the main shaft 21, through an intermediate gear 58, drives a gear 59 mounted on a shaft 60. The latter has two spiral gears 61 driving spiral gears 62 which are mounted on shafts 63 operating the ink distributors of the two printers.

The shaft 29 carries a bevel gear 64 meshing with a bevel gear 65 on a shaft 66 which has a bevel gear 67 meshing with a bevel gear 68 on a horizontal shaft 69 driving the paster 90 H of the cigarette rod A. Similarly, the shaft 30 carries a bevel gear 71 meshing with a bevel gear 72 on a shaft 73 having a bevel gear 74 meshing with a bevel gear 75 on a horizontal shaft 76 which drives the paster H of the cigarette rod B.

On the shaft 29 is also mounted a gear 78 meshing with a gear 79 mounted on a shaft 80. The latter carries a worm 81 driving a wormwheel 82 which is mounted on a shaft 100 83. The wormwheel 82, through a pawl 84, drives a ratchet 85 mounted on a shaft 86 on which is supported the tape wheel of the cigarette rod B. On the shaft 30 is mounted a worm 88 meshing with a wormwheel 89 keyed to a shaft 90 which, through a pawl 91, drives the ratchet 92 on a shaft 93 driving the tape wheel 94 of the cigarette rod A.

The jackshaft 44, by means of a pulley 95 and belt 96, drives the pulley 97 of the two rod sealers J.

On the jack shaft 44, is mounted a clutch 98 to which is attached a bevel gear 99 meshing with the bevel gear 100 on a shaft 101. The latter, through bevel gears 102 and 103, drives the shaft 104 carrying the eccentric 105 operating the cutoff K.

A bevel gear 106 on the jackshaft 44 meshes with a bevel gear 107 on a shaft 108 carrying a bevel gear 109 meshing with a bevel gear 110 on a shaft 111 which carries a pulley 112 driving the cigarette separator belts N of the rods A and B. The belts N run on the guide pulleys 113 and are kept in tension by the idlers 114 of the belt tighteners 115.

To the clutch 98 and the bevel gear 99 is attached a sprocket 116 which, through a silent chain 117, drives a sprocket 118 on a shaft 119. The latter carries a pulley 120 which, through a belt 121, drives a pulley 122

122 on a shaft 123 carrying the knives 124 and 125 of the ripper Q. A drum 126 on the shaft 119 drives the ripper belt 127. The shaft 119 also has a spiral gear 128 meshing with another spiral gear 129 fastened to a shaft 130 on which is mounted an eccentric arm 131 imparting to the bottom of the ripper Q a reciprocating motion. The ripper is provided with a screen 132 for separating the tobacco from the paper.

On the shaft 108 is mounted a spiral gear 133 meshing with the spiral gear 134 on the shaft 135, the plan view of which is shown in Fig. 10. To the shaft 135 is keyed a bevel gear 136 meshing with the bevel gear 137 mounted on a shaft 138 which drives a catcher drum 139 having the belts 140 running over adjustable idler pulleys 141. The pulleys 141 are mounted on shafts 142 supported in forked tightener arms 143 which are hinged on a shaft 144. The arms 143 are provided with adjusting screws 145 having hand wheels 146 for tightening the belts 140. The spiral gear 133 also meshes with a spiral gear 147 on a shaft 148 having a sprocket 149 which, through a chain 150, drives a sprocket 151 actuating the ejecting wheels 152.

On the main shaft 121, as shown in Fig. 3, is mounted a gear 153 meshing with a gear 154 on a shaft 155 carrying a pinion 156 which, through an intermediate gear 157, drives a gear 158 mounted on a shaft 159 having also a gear 160 which meshes with a gear 161 on a shaft 162. The latter has a gear 163 meshing with a gear 164 on a feed clutch shaft 165 having two clutches 166, one for each cigarette rod. By stopping either one of the rods, its tobacco feed is thereby automatically shut off.

The shaft 165 has a sprocket wheel 167 which, through a chain 168, drives a sprocket wheel 169 on a shaft 170 of the lower drum of the left hand tobacco feed which supplies the cigarette rod B. The chain 168 runs over an idler sprocket 171 and is kept in tension by a tightener sprocket 172. The shaft 170 carries a sprocket 173 which, through a chain 174, drives sprockets 175, 176 and 177. The sprocket 175 is mounted on a shaft 178 driving the short feed belt of the tobacco feed for the cigarette rod B. The sprocket 176 is mounted on a shaft 179 driving the long feed belt of the tobacco feed for the cigarette rod B. The sprocket 177 is fastened to the shaft 180 of a concave roller 181 of the feed for the rod B. On the shaft 179 is mounted a gear 182 meshing with the gear 183 on the shaft 184 driving the compression roller 185 of the feed for the rod B. The chain 174 runs over idlers 186 and 187. With the shaft 184 rotates a pronged wheel 188 striking a lever 189 which, through a shaft 190, operates a hammer which knocks against the rear wall of the chute 191, setting the same in vibration so that no dust or tobacco will stick to it.

The tobacco chamber of each feed has an adjustable wall controlling the quantity of tobacco fed to the cigarette rod. The adjusting wall of the feed for the rod B is fastened on the rods 192 and 193 having sprockets 194 and 195 respectively which are connected by a chain 196. On the rod 193 is mounted a sprocket 197 which, through a chain 198, is connected with a sprocket 199 mounted on a shaft 200 to which a crank or handle is attached in case adjustment is required. The chain 198 is kept in tension by a tightening sprocket 201.

On the shaft 159 is mounted an eccentric 202 connected through a rod 203 to a lever 204 pivoted on a shaft 205. To the lever 204 is hinged a rod 206 connecting it with the drive arm 207 pivoted on a shaft 208. To the shaft 208 is attached the upper drum of the tobacco feed for the rod B, and also a ratchet wheel 209 which is driven step by step by a pawl 210 pivoted on the arm 207. In order to prevent the shaft 208 from turning during the advance of the pawl 210, the ratchet 209 is provided with a brake drum 211 having a brake band 212 which is kept in tension by a spring 213. To the shaft 208 is pivoted a lever 214 having a pawl 215 preventing back-sliding of the ratchet. The drive of the tobacco feed for the forward cigarette rod A is located at the opposite side of the feed box E and is a duplicate of that shown in Fig. 3, the mechanism in this case being driven from the clutch shaft 165. By means of the clutches 166, then, either of the feeds may be stopped without affecting the operation of the other.

The top fan, which is common to both feeds, is mounted on a shaft 216 and runs all the time when the machine is in operation. It is driven from a pulley 217, Fig. 1a, through a belt 218 running over a pulley 219 on a shaft 220 on which is also mounted the common winnower. The shaft 220 has a double pulley 221 which, through a belt 222, drives a pulley 223 on the shaft 224 carrying the common picker roll of the two feeds. The double pulley 221, through a belt 225, is driven from a pulley 226 on a shaft 227 supported by a bearing bracket 228 on the main base 11. The shaft 227 also has a pulley 229 which, through a belt 230, is driven from a pulley 231 on a shaft 232 of the Reeves drive 17. The shaft 227 further has a pulley 233 which, through a belt 234, drives the suction fan 235.

The drive control system by which it is made possible to stop the mechanism of either cigarette rod while that of the other is operating, is shown in Figs. 4 to 9. The shafts 29 and 30 have each a specially designed clutch 236 and 237 respectively, so arranged that both clutches can be in engagement, or either clutch can be engaged and the other disengaged, but both clutches cannot be disengaged at the same time. To achieve this object, the shafts 29 and 30 are provided with

sleeves 238 which hold springs 239 bearing against one end of the sleeve 238 and against stationary collars 240 fastened to the shafts 29 and 30. The collars 240 are provided with two diametrically opposite axial slots in which are pivoted lock fingers 241 engaging grooves 242 of the sleeve 238 when the latter are held in locking position against the tension of the springs 239. Each shaft 29 and 30 has a diametrical hole containing a spring 243 which bears against the lock fingers 241 which are held in place by the operating sleeves 244 and 244^a. The latter have central collars 245 and 245^a through which they are moved back and forth by rods 246 and 246^a having collars 247, 248, 247^a and 248^a, spaced in such a manner that when the collar 247 engages the collar 245 to move the operating sleeve 244 in one direction, the collar 248^a engages the collar 245^a and moves the operating sleeve 244^a in the opposite direction. The rods 246 and 246^a are pivoted in the ends of a double lever 249 mounted on a shaft 250 vertically supported in bearing brackets 251 and 252. On the shaft 250 is mounted a gear sector 253 meshing with a gear sector 254 mounted on a shaft 255 having a hand lever 256. The collars 247, 248, 247^a and 248^a are so spaced on the rods 246 and 246^a that in the central position of the operating lever 256, both clutches are in engagement. In order to disengage one or the other of them, it is only necessary to move the hand lever 256 either to the right or to the left.

When the clutch operating sleeve 244 or 244^a is moved to the left, its beveled bore 257 presses the lock fingers 241 inward and out of engagement with the groove 242 of the sleeve 238, and the then released spring 239 pushes the male clutch disc 258 into engagement with the female clutch disc 259. In order to disengage the clutches, the rods 246 and 246^a are provided with slotted heads 260 and 260^a which engage pins 261 and 261^a fastened to clutch shifting forks 262 and 262^a mounted on shafts 263 and 263^a supported in a bearing bracket 264 attached to the frame 11. By disengaging one of the clutches 236 or 237, as shown by arrows in Fig. 5, the operating rod of the other clutch will be pulled in the opposite direction, thereby disengaging the lock fingers 241 of that clutch if they are not already disengaged, and causing its spring 239 to throw it into engagement. As by this arrangement it is only possible to disengage one clutch at a time, stopping either one of the cigarette rods but not both simultaneously, the main shaft 21 of the machine is provided with a main clutch 265 which will, when disengaged, stop the entire machine.

The main clutch 265 is operated from the main shift lever 266 mounted on a shifter shaft 267 supported by bearing brackets 268 and 269. The shift lever 266 is guided by a

rod 270 mounted in a bracket 268. On the shaft 267 is slidably mounted a slide cam 271 which is placed between two set collars 272 so that it can move freely through a certain distance before pushing the shaft 267 in either direction. The slide cam 271, through a link 273, is connected to a lever 274 mounted on a shaft 275 which is supported by brackets 70 70 and 77, and also has the hand lever 276. In order to operate the main clutch from the opposite side of the machine, the shaft 275 has a lever 277 connected through a rod 278 to a bellcrank lever 279 which, by a rod 280, is connected to a lever 281 fulcrumed with the hand lever 282 on a shaft 283 supported by 75 75 a bracket 284.

The machine is started by operating one of the hand levers 276 or 282, that is, by engaging the main clutch 265. The machine always starts at sub-normal speed. In order to accelerate the speed, the speed lever 285 (Fig. 6) is pulled over slowly until arrested by the stop pin 286 (Fig. 7). The speed lever 285 is mounted on a shaft 287 supported in brackets 288 and 289 and having a lever 290 which, through a rod 291, is connected with a lever 292 on a shaft 293 carried by bearing brackets 294, 295 and 296. The shaft 293 also carries a lever 297 which, through a rod 298, is connected with the Reeves drive gearing 17. 95

The machine now running at high speed: If for any reason it is necessary to stop one of the cigarette rods, it will be necessary to first bring the machine back to low speed. For this purpose, all levers for disengaging clutches are connected with the Reeves drive gearing and will bring the machine to low speed automatically before disengaging a clutch. To so connect the individual rod operating levers, the gear sector 253 is provided with a cam 299 moving with the sector, and a roller 300 is mounted in the end of a lever 301 on the shaft 293 so as to bear against the cam surface. The cam 299 is so shaped that, in the clutch disengaging position of the sector 253, the lever 301, through the shaft 293, lever 297 and rod 298, throws the Reeves gearing into low speed. Similarly, the slide cam 271, operating the main clutch 265, bears against a roller 302 mounted in an arm 303 fastened to the shaft 293, thereby operating the Reeves gearing before disengaging the main clutch. 100

The rod operating clutches 236 and 237 can also be manipulated from the opposite side of the machine by means of a lever 304 mounted on the shaft 283 having a lever 305 which, through a rod 306, is connected with a bellcrank lever 307 attached to a rod 308 which is pivoted in a forked bracket 309 and on which is also mounted a bellcrank lever 279. The lever 307, through a rod 310, is connected to a lever 311 attached to the gear sector 254. 105

On the shaft 250 is mounted a gear sector 312 meshing with a gear sector 313 on a shaft 130

814 supported in a bearing bracket 315 attached to the tobacco feed E. On the shaft 814 is secured a lever 316 which, through a rod 317, is connected to the two feed control 5 clutches 166 on the feed clutch shaft 165. The sector 312 moves in unison with a lever 249, so that, when either of the cigarette rods is stopped by the lever 249, the corresponding tobacco feed is also discontinued. In order 10 to stop either feed independently of the operation of the cigarette rod forming mechanism, the rod 318 is provided which controls the two feed clutches by hand.

In view of the foregoing, a detailed description 15 of the operation of the machines is deemed unnecessary and is therefore omitted in the interest of brevity.

What is claimed is:

1. The combination with cigarette making 20 mechanism, of a constant speed source of motion, a main shaft for driving said mechanism, speed varying gearing and a clutch connecting said source with said shaft, and controlling means including operating connections to said clutch and said gearing for causing said shaft to start only at subnormal speed and devices for accelerating said speed after starting.

2. The combination with cigarette making 25 mechanism, of a constant speed source of motion, a main shaft for driving said mechanism, speed varying gearing and a clutch connecting said source with said shaft, and controlling means including operating connections to said clutch and said gearing for causing said shaft to start only at subnormal speed and devices for accelerating said speed after starting, said mechanism including a jack shaft driven by said main shaft and two 30 printing dies driven by said jack shaft and controlled by said means.

3. The combination with cigarette making 35 mechanism, of a constant speed source of motion, a main shaft for driving said mechanism, speed varying gearing and a clutch connecting said source with said shaft, and controlling means including operating connections to said clutch and said gearing for causing said shaft to start only at subnormal speed and devices for accelerating said speed after starting, said mechanism including a jack shaft driven by said main shaft, and cutoff mechanism driven by said jack shaft and controlled by said means.

4. The combination with cigarette making 40 mechanism, of a constant speed source of motion, a main shaft for driving said mechanism, speed varying gearing and a clutch connecting said source with said shaft, and controlling means including operating connections to said clutch and said gearing for causing said shaft to start only at subnormal speed and devices for accelerating said speed after starting, said mechanism including a 45 jack shaft driven by said main shaft and two

cigarette catchers driven by said jack shaft and controlled by said means.

5. The combination with cigarette making 50 mechanism, of a constant speed source of motion, a main shaft for driving said mechanism, speed varying gearing and a clutch connecting said source with said shaft, and controlling means including operating connections to said clutch and said gearing for causing said shaft to start only at subnormal speed and devices for accelerating said speed after starting, said mechanism including a jack shaft driven by said main shaft, and a cigarette ripper driven by said jack shaft and controlled by said means.

6. The combination with cigarette making 55 mechanism, of a constant speed source of motion, clutch means and speed varying gearing connecting said source with said mechanism, and controlling means connected to said clutch means and said gearing for automatically causing said gearing to drive the mechanism at subnormal speed preliminary to disengagement of the clutch means to insure low speed driving when starting and stopping.

7. The combination with cigarette making 60 mechanism, of a constant speed source of motion, clutch means and speed varying gearing connecting said source with said mechanism, and controlling means connected to said clutch means and said gearing for automatically causing said gearing to drive the mechanism at subnormal speed preliminary to disengagement of the clutch means to insure 65 low speed driving when starting and stopping, and means acting on said gearing for accelerating said mechanism to normal speed after starting.

8. The combination with cigarette making 70 mechanism, of a constant speed source of motion, clutch means and speed varying gearing connecting said source with said mechanism, and controlling means connected to said clutch means and said gearing for automatically causing said gearing to drive the mechanism at subnormal speed preliminary to disengagement of the clutch means to insure 75 low speed driving when starting and stopping, said mechanism including two rod forming mechanisms and said clutch means having separate clutches through which each of said rod forming mechanisms are driven, and means for selectively operating said 80 clutches.

9. The combination with cigarette making 85 mechanism, of a constant speed source of motion, clutch means and speed varying gearing connecting said source with said mechanism, and controlling means connected to 90 said clutch means and said gearing for automatically causing said gearing to drive the mechanism at subnormal speed preliminary to disengagement of the clutch means to insure 95 low speed driving when starting and stopping.

stopping, said mechanism including two rod forming mechanisms and said clutch means having separate clutches through which each of said rod forming mechanisms are driven, and a connection between said clutches operative to permit either one of said clutches to be disengaged but preventing disengagement of both at once.

In testimony whereof, I have signed my name to this specification.

JOHN A. STEIN.
